UNITED STATES PATENT OFFICE.

ALLISON J. THOMPSON, OF CLEVELAND, OHIO.

LAMP FIXTURE.

Application filed July 6, 1920. Serial No. 394,341.

To all whom it may concern:

Be it known that I, ALLISON J. THOMPSON, a citizen of the United States, residing at Cleveland, in the county of Cuyahoga and 5 State of Ohio, have invented certain new and useful Improvements in Lamp Fixtures, of which the following is a specification.

This invention relates to the class of illumination and more especially to lamp 10 hangers.

The type of device to which my invention relates comprises in a general way a main hanger member which is fixedly supported in an elevated position and a lamp hanger 15 member which is detachably locked to the upper or main hanger member so that the lower member can be released and lowered by means of a cable for the purpose of inspection, cleaning the reflector, and renewal 20 of the parts. The improvements in the present invention relate particularly to the structure and arrangement of the mechanism for locking the two hanger members together; to the structure and arrangement of the contact 25 members for closing the circuit to the lamp when the hanger members are locked together, and to the outlet connection for the lamp.

Fig. 1 is a front view of my invention 30 partly in full view and partly in section; Fig. 1^a is a partial sectional view on the line 1^a—1^a of Fig. 1; Fig. 2 is a side view partly in full view and partly in section; Fig. 3 is a detail view of the latch mechanism; Fig. 4 is an inverted plan view of one of the female 35 contact members; Fig. 5 shows in elevation one of the male contact members; and Fig. 6 shows the supporting attachment when an arc lamp is used.

40 The sheave housing 1, provided with brackets 2 and 3, has pivoted therewithin the sheave 4 which is mounted upon the pin 5, the outer ends of which carry the insulators 6 and 7. The cable 8 enters the housing 1 through the throat 9 and passes about the sheave in a well known manner. Flanges 12 on housing 1 are attached to the canopy 11 by means of the screws 10.

The mechanism enclosed in the canopy 50 11 will now be described. The same screws 10 which secure the canopy to the flanges 12 of the sheave housing serve also to secure in position within the main hanger member the tubular guide 13 which is slotted through 55 its full length as indicated at 14. The lower end of the guide 13 is formed with a cam

face as indicated at 15 for the purpose of rotating the lamp hanger member so as to properly align the lower contacts with the upper contacts. Tubular guide 13 is provided with flange portions 16 and 17 along the margins of the longitudinal slot 14 and these flanges are provided with notches as indicated at 18 for a purpose to be later pointed out. As will be noted from the drawings the flanges 16 and 17 taper in their depth toward their upper ends and have their lower ends curved so as to merge into the curvature of the cam portion 15. Circular ribs 13^a and 13^b on the inner face of 70 the tubular guide 13 afford bearing surfaces for the latch stem carried by the lamp hanger member, as will later appear. The top of the canopy is provided with an aperture registering with the opening through 75 the tubular guide 13. As will be seen from the drawings, this aperture is of a key hole form which conforms in a general way to a cross section through the tubular guide 13 in a plane near the upper end thereof. This 80 key hole aperture allows the upper end of the latch stem carried by the lamp hanger to pass through the top of the canopy.

Duplicate female contact members are 85 supported within the canopy 11 and are attached to the top wall thereof. These contact members 19 and 20 are arranged on opposite sides of the tubular guide 13, and since they are of the same construction, a description of one of these members will 90 suffice. A block of porcelain or other suitable insulating material is secured to the canopy by any suitable means, as for instance bolts 22 and 23 which extend through the ears 24 and 25. The female contact, 95 which may be formed of brass, copper or other suitable material, is flared outwardly and has a concave spherical contact surface as shown in the drawings. This contact is secured to the block 21 by means of the screw bolt 28, washers 29 and 30 of conductive material being provided for the clamping of the lead wire. The lead wire is received through the cut-away portion provided in the depending flange 26. Sealing-wax or 100 other insulating plastic material fills the space around the nut end of the screw bolt 28 as clearly indicated in Fig. 1. Insulating bushings 31 are provided for leading in the wires through the wall of the canopy 11. 105 The depending flange 26 increases the insulation between the point where the lead

wire is attached to the contact and the nuts on bolts 22 and 23, and thus the possibility of the current jumping between these two points is minimized by the flange 26.

5 The lamp hanger member, which carries the lamp and reflector, carries also contacts for engagement with the contacts carried by the main hanger member. Upon raising the lamp hanger member, the upper part of 10 fin 41 on the latch stem engages the cam surface 15 and thereby causes the lamp hanger member to rotate until the fin is in alignment with the slot 14 and the lower contacts are brought into alignment with the 15 upper contacts. The contacts are then brought into engagement and the two hanger members are brought into locked relation. Then upon unlocking the two hanger members, the lamp hanger is lowered and the 20 contacts are separated.

The lamp hanger member is provided with a latch stem 14 which passes up through the tubular guide 13, the latch dog 42 being pivotally mounted upon the fin 41 on the 25 latch stem 14. The lower portion of the fin 41 has greater radial extent with respect to the latch stem than the upper portion thereof. This arrangement is for the purpose of allowing proper radial movement of 30 the dog in locking and unlocking the same, as will be seen from Fig. 1. The dog is of a clevis form and is pivoted upon the enlarged portion of the fin 41 by means of the pin 43. The dotted lines represented at 35 44 indicate the point where the full or base portion of the latch stops, or, in other words, indicates the extent to which the latch can swing upwardly before striking the fin 41. This arrangement constitutes a stop for the 40 dog in its upward swinging movement. The fin 41 is located with respect to the notches 18 so that the tail of the dog 42 will swing into locking engagement therewith.

The latch dog 42 is shaped eccentrically 45 with respect to its pivotal point, and that portion indicated at 42^a which is on the side of the pivot point away from the tail of the dog, is sufficiently heavy to cause a quick swinging of the dog about its pivot in a counter-clock-wise direction upon release thereof, as viewed in Figs. 2 and 3, as will be later explained. The tail of the dog has a face 42^b which engages the upper edge of 50 the notches upon raising the latch stem in the unlocking operation; while the face 42^c of the dog is adapted to engage the lower edge of the notches as the latch stem is lowered. The face 42^c is so formed that there is no danger of the dog sticking on the lower 55 edge of the notches or swinging into the notches during the movement of this face down past the lower edge thereof. It is also noted that the tail of the dog, when in locked position, extends in an approximate- 60 ly horizontal direction and abuts against the bottom 18^a of the notches and the lower face of the tail of the dog engages the lower side 18^b of the notches. That is to say, one component of force is directed in a horizontal plane against the side of the tubular guide 70 and another component of force is directed in a vertical direction against the lower part of the flanges 16 and 17. The first named component of force effects a decided binding action between the latch stem and the tubular guide in a substantially horizontal plane. Both of these components of force vary directly as the weight suspended from the latch stem. It is further pointed out that the binding action referred to can be increased by placing the pivotal point of the dog farther away from the tubular guide, or, in other words, by increasing the degree of eccentricity of the dog to which reference 75 was made above. The binding action referred to can also be increased by locating the notches 18 midway of the bearing ribs 13^a and 13^b.

The cable 8 extends through the latch stem 14 and its knotted lower end engages the apertured disk 39 which in turn engages across the lower end of the opening through the latch stem. In this way a means is provided for raising the lamp hanger member, although other suitable means might be adapted for effecting engagement between the cable and the lamp hanger member. The lower enlarged end portion of the latch stem is surrounded by coil spring 34, the 80 ends of which abut the flange 36 on the end of the latch stem and the inwardly projecting flanges on the upper part of the cylindrical housing 32, one of which last named flanges is shown in section at 33. The other flange 33^a is of the same width as flange 33. The flanges 33 and 33^a are forced by the spring 34 into abutting engagement with the lugs 35^a which project radially from the latch stem. The flanges 33 and 33^a are provided with recesses 37 to receive the lower portions 38 of the lugs 35^a so as to prevent axial turning of the latch stem within the housing 32. The purpose of the spring 34 is to permit upward movement of the latch stem against the tension thereof independently of the housing 32 and the contact members carried thereby, as will now be more fully set forth.

The lower end of the latch stem has screw threaded engagement with the outlet connector member 60 through which extend the wires to the lamp which is attached to the screw threads 61, in case an incandescent lamp is used. As will be seen from Fig. 1, the wires from the two sides extend through the diametrically opposed sides of the outlet, as indicated at 62 and 62', and thence through the neck 63 to the lamp socket. In case an arc lamp should be used, the plug attachment shown in Fig. 6 is screwed into 105 110 115 120 125 130

the lower end of the latch stem and the arc lamp is supported from the loop 65.

The housing member 32 is provided with diametrically opposed webs 45 and 46 extending upwardly therefrom and terminating in the horizontally disposed ears 47 and 48. These ears are apertured and receive floating contact members which are duplicates and only one of which will therefore be described. The lower insulating member is provided with a boss 49 which extends upwardly through the aperture in the ear 48 and is formed on its lower side with a depending skirt or flange 50 which has a cut-away portion 51 to accommodate the reception of the lamp wire, as clearly shown in Figs. 1 and 4. The flange 50 minimizes the possibility of the current jumping across from the end of the lamp wire to the metal wall of the housing 32 and in this way increases the insulation. As illustrated in Fig. 4, the depending flange 50 is curved throughout a portion thereof to conform to the curvature of the housing member 32 and is spaced therefrom to allow movement of the insulating member in a horizontal plane. An upper insulating member 52 engages the boss 49 on the lower insulating member, a cushion washer of paper or other insulating material being provided between the faces of these two insulating members for the purpose of compensating for expansion and contraction of the parts. These insulating members are provided with registering apertures for the screw bolt 54 which extends therethrough. The inner portion of wall 50 prevents turning of the nut of the screw bolt and hence facilitates assembly of the parts. A sleeve 55' of insulating material surrounds the screw bolts 54. Washers 55 and 56 of conductive material are clamped against the under face of the lower insulating member 50 so as to provide a binding post for the lamp wire. A contact 57 is clamped in position upon the upper face of the insulating member 52 by means of the screw bolt 54 and a cushion washer 58 of suitable insulating material is provided to compensate for expansion and contraction of the parts. The contact 57 is cup shaped with its engaging contact surface formed as a segment of a sphere so as to allow universal engagement with the female contact carried by the upper hanger member. As clearly indicated in Fig. 1, the contact 57 is hollowed out so as to allow insertion of the screw bolt therethrough. The tapered boss 49 is of greater extent than the thickness of the ear 48 and has play in a horizontal plane in the aperture of ear 48. Thus the contacts carried by the lamp hanger member are capable of movement both in vertical and horizontal planes and are therefore said to be yielding or floating.

In assembling the parts, for use with an incandescent lamp, the wires from the lamp are passed up through the neck 63 and are allowed to project straight up through the open upper end thereof. The lower end of the connector is then screwed into the lamp socket and the upper ends of the wires are next passed down through the side extensions 62 and 62'. Then the connector member carrying the lamp is screwed into the lower end of the lamp hanger member and the upper ends of the wires are attached to the binding posts. Thus with this arrangement there is avoided any twisting of the wires.

The operation of this device will now be described. First, assume the lamp hanger member to be disengaged from the main hanger member. Upon raising the lamp hanger member by means of the cable the latch stem will enter and pass through the tubular guide, and the lower male contacts will in this way be guided into engagement with the upper female contacts. Upon further lifting action being applied to the cable the latch stem will continue to rise, causing compression of the spring and in this way bring the contacts into engagement under firm tension. Further raising of the latch stem causes the tail of the dog to ride up over the flanges 16 and 17, to a point opposite or above the notches 18, whereupon it will swing into engagement therewith upon slowly lowering the latch stem. When it is desired to disengage the two hanger members the latch stem is raised against the tension of the spring, whereupon the tail of the dog rides up over the upper edges of the notches 18. Then by quickly releasing the cable, the dog is carried downwardly past the notches before its tail has time to swing into the notches. The lamp hanger member is then wholly disengaged from the main hanger member and can be lowered for purposes of inspecting or renewing the parts carried thereby and also for cleaning the lamp reflector.

Thus it will be seen that the lamp hanger member can be readily lowered to permit cleaning of the reflector as well as inspection and renewal of all of the parts, including the lamp, the latch dog and the floating contacts. The location of the latch dog and floating contacts upon the lamp hanger member constitutes a very important advantage in connection with my present device. Furthermore, my particular latch mechanism has a decidedly positive action and produces a very effective binding or pinching engagement between the latch stem and the tubular guide when these parts are locked together. The particular structure and arrangement of my insulating means for both the upper and lower contacts constitutes another advantage of this invention;

as also the particular floating arrangement of the male contacts which insures proper engagement thereof with the female contacts. A further advantage resides in the 5 fact that I avoid the objectionable twisting of the wires in attaching a lamp to the lamp hanger member.

What I claim is:

1. In a lamp hanger, a main hanger member, a lamp hanger member, latching mechanism for locking said members together, fixed contacts carried by the main hanger member and individually floating contact members carried by the lamp hanger member, each of 10 said floating contacts comprising a sectional insulator and a contact member, and a single means for securing together said insulator sections and the contact member.
2. In a lamp hanger, a main hanger member, a lamp hanger member, latching mechanism for locking said members together fixed contacts carried by the main hanger member, individually floating contact members carried by the lamp hanger member and 15 co-operating with the fixed contacts of the main hanger member, apertured supports for said floating contact members, each of said floating contact members comprising an insulating means loosely mounted in said 20 aperture, said insulating means having vertical and lateral movement in said aperture, and a contact carried by said insulating means.
3. In a lamp hanger, a main hanger member, a lamp hanger member, latching mechanism for locking said members together, fixed contacts carried by the main hanger member and having concave spherical contacting surfaces, said concave surfaces being 25 spaced from the main hanger member individually floating contact members carried by the lamp hanger member, said last named hollow contact members having convex 30 spherical contact faces for co-operation with said fixed contacts, bolts securing said contact members to said lamp hanger member and arranged with their heads seated within 35 said hollow contact members.
4. In a lamp hanger, a main hanger member, a lamp hanger member, latching mechanism for locking said members together, fixed contacts carried by the main hanger member, individually floating contact members carried by the lamp hanger member and 40 co-operating with the fixed contacts of the main hanger member, apertured supports for said floating contact members, each of said floating contact members comprising a 45 sectional insulator extending through said aperture support and carrying a contact, and a single means for clamping together said insulator sections and said contact.
5. In a lamp hanger, a main hanger member of non-insulating material, a lamp 50

hanger member, separate insulating blocks carried by the main hanger member, contacts mounted upon said blocks and approximately in the main axis thereof, means for attaching lead wires to said contacts, said 55 blocks being provided with flanges of insulating material depending below the points of attachment of the lead wires to prevent jumping of the current, said depending flanges having cut-away portions to facilitate connection of the lead wires to said 60 contact members, and contacts carried by said lamp hanger member for co-operation with said first named contacts.

6. In a lamp hanger, a main hanger member, a lamp hanger member, latching mechanism for locking said members together, fixed contacts carried by the main hanger member, individually floating contact members carried by the lamp hanger member and co-operating with the fixed contacts of the main hanger member, apertured supports for said floating contact members, each of said floating contact members comprising a sectional insulator extending through said apertured support and provided with a depending flange, a contact carried by said insulator, and a single means for clamping together said insulator sections and said contact, said 65 means including a screw bolt and nut, said depending flange extending in sufficiently close proximity to said nut to prevent turning of same on said bolt.

7. In a lamp hanger, a main hanger member, a lamp hanger member, insulating blocks for said main hanger member, means for securing said blocks to said main hanger member, said means including nuts and screw bolts, said screw bolts extending through said blocks, said blocks being provided with means to engage said nuts and thereby prevent the same from turning upon 70 said bolts.

8. In a lamp hanger, a main hanger member, a lamp hanger member, a slotted guide tube carried by one of said members, a latch stem carried by said other member and adapted to be received by said slotted tube, a latch dog carried by said stem and means provided upon the outside of said slotted tube for locking engagement with said latch dog.

9. In a lamp hanger, a main hanger member, a lamp hanger member, co-operating contacts carried by said members, a slotted guide tube carried by said main hanger member, a latch stem carried by said lamp hanger member and adapted to be received by said slotted tube, a latch dog carried by 100 said stem and means provided upon the outside of said slotted tube for locking engagement with said latch dog.

10. In a lamp hanger, a main hanger member, a lamp hanger member, co-operat- 105

- ing contacts carried by said members, a slotted guide tube carried by said main hanger member, a latch stem carried by said lamp hanger member and being provided 5 with a fin extending longitudinally thereof, said slotted tube being adapted to receive said stem with its fin, a latch dog pivoted upon the outside of said fin, engaging means provided upon said tube for locking engagement with said latch dog and means provided upon said guide tube in the path of 10 said latch dog as it is moved in an upward direction for causing said dog to swing out and clear said engaging means downward 15 movement thereof in the unlatching operation.
11. In a lamp hanger, a main hanger member, a lamp hanger member, co-operating contacts carried by said members, a slotted guide tube carried by said main hanger member, a latch stem carried by said lamp hanger member and being provided 20 with a fin extending longitudinally thereof, said slotted tube being adapted to receive said latch stem with its fin, a latch dog pivoted upon said fin, said guide tube being provided with bearing ribs upon its inner face and with a notch located between said ribs 25 to receive said dog, the tail of said dog being eccentrically arranged with respect to its pivot point and extending in an approximately horizontal direction when in locked position, whereby there is caused a clamping of said dog against the side of said guide tube and a binding or pinching action 30 through an approximately horizontal plane 35 is effected between the guide tube and the latch stem.
12. In a lamp hanger, a main hanger member, a lamp hanger member, co-operating contacts carried by said members, a slotted guide tube carried by said main hanger member, a latch stem carried by 40 said lamp hanger member and adapted to be received by said slotted tube, a latch dog carried by said latch stem, means provided upon the outside of said slotted tube for locking engagement with said latch dog, and 45 means for causing disengagement of said latch upon upward movement of said latch stem, thereby allowing said lamp hanger member to be lowered away from said main hanger member.
13. In a lamp hanger, a main hanger member, a lamp hanger member, co-operating contacts carried by said members, a slotted guide tube carried by said main hanger member, a latch stem carried by said lamp 50 hanger member and being provided with a fin extending longitudinally thereof, said slotted tube being adapted to receive said latch stem with its fin, a latch pivoted upon the outside of said fin, dog receiving means provided upon said tube for locking engagement with said latch, and means provided upon said guide tube in the path of 55 said latch as it is moved in an upward direction for causing said dog to swing out and clear said dog receiving means on down- 60 ward movement thereof in the unlatching operation, the tail of said latch dog being eccentrically arranged with respect to the pivot point thereof and extending in an approximately horizontal direction when in locked position, whereby there is caused a clamping of said dog against the side of said guide tube and a binding or pinching action 65 through an approximately horizontal plane 70 is effected between the guide tube and the latch stem.
14. In a lamp hanger, a main hanger member, a lamp hanger member, co-operating contacts carried by said members, a slotted guide tube carried by said main hanger member, a latch stem carried by said lamp hanger member and being provided with a fin extending longitudinally thereof, said slotted tube being adapted to receive said latch stem with its fin, said guide tube being provided 80 with bearing ribs upon its inner face and with a notch located between said ribs to receive said dog, the tail of said dog being eccentrically arranged with respect to its pivot point and extending in an approximately horizontal direction when in locked position, whereby there is caused a clamping of said dog against the side of said guide tube and a binding or pinching action 85 through an approximately horizontal plane 90 is effected between the latch stem and the bearing ribs on said guide tube.
15. In a lamp hanger, a main hanger member, a lamp hanger member, a slotted guide tube carried by one of said members, a latch stem carried by said other member and adapted to be received by said slotted tube, a latch dog pivotally mounted upon said latch stem and lying outside of said tube and being weighted at the side of the pivot 100 point away from the tail of the dog and means provided upon the outside of said slotted tube for locking engagement with the tail of said latch dog.
16. In a lamp hanger, a main hanger member, a lamp hanger member, co-operating contacts carried by said members, a slotted guide tube carried by said main hanger member, a latch stem carried by said lamp hanger member and being provided 105 with a fin extending longitudinally thereof, said slotted tube being adapted to receive said latch stem with its fin, a latch pivoted upon said fin, said guide tube being provided on the outside thereof with a recess 110 adapted to receive said latch dog in locking engagement, the tail of said latch dog having a face for engagement with the upper edge of said recess to cause said dog to swing out of said recess, and the tail of said dog having also a face which is adapted to ride down over the lower edge of said recess, upon lowering of said latch stem, so that said dog will clear said recess.
17. In a lamp hanger, a sectional insulat- 115

ing support for an electric contact comprising an insulating member having a recess in one face thereof, a second insulator member having a boss for engagement in said 5 recess, a screw bolt extending through said members and adapted to secure also an electric contact upon said first named insulator member, said boss being of sufficient extent to provide space between the adjacent faces 10 of said members for the engagement with an apertured support, means upon the end of

the screw bolt for attaching an electric wire, said second named insulator member being provided with a flange of insulating material extending past the point of attachment 15 of the wire and said flange having a cut-away portion to facilitate attachment of the wire.

In testimony whereof I affix my signature.

ALLISON J. THOMPSON.
